UNITED STATES PATENT OFFICE.

HENRY JEFFERSON DAVIS, OF WAYNESBORO, GEORGIA.

VENDING-MACHINE.

1,295,971.

Specification of Letters Patent.

Patented Mar. 4, 1919.

Application filed March 18, 1918. Serial No. 223,137.

To all whom it may concern:

Be it known that I, HENRY JEFFERSON DAVIS, a citizen of the United States, and resident of Waynesboro, county of Burke, State of Georgia, have invented certain new and useful Improvements in Vending-Machines, of which the following is a specification.

The present invention relates to improvements in vending machines, being particularly adapted for machines intended to sell bottled goods, such as coca cola. The particular object of the invention is to provide a simple and effective mechanism by which after a bottle has been emptied it may be returned to a suitable receptacle or compartment of the machine and a coin representing the value of such empty container delivered.

In the accompanying drawings the outer casing or framing of the machine is only partially shown and many of the features of the mechanism illustrated are shown more or less diagrammatically.

In the drawings, Figure 1 is a sectional view substantially on the line 1—1 of Fig. 3;

Fig. 2 is a similar view on the line 2—2 of Fig. 3;

Fig. 3 is an elevation of the parts shown in Figs. 1 and 2.

Referring to the drawings the improved machine comprises a frame or casing 1 which is interiorly divided into two compartments or chambers by an inclined floor 2, said floor serving as a support for a series of bottles 3 and the space, or a portion thereof, below said floor serving as a receptacle for empty bottles.

Coin controlled means are provided for successively withdrawing the bottles 3 from the compartment or chamber above the floor 2 in which they are stacked and delivering the same to a chute 4 that extends to the outside of the machine and has portions of its sides adjacent the lower end removed so that a bottle may be readily withdrawn therefrom.

As shown, the bottle withdrawing means comprises two members 5 provided with peripheral pockets each adapted to receive a bottle 3 and secured upon a shaft 6 which is mounted in suitable bearings in the frame of the machine. At one end of said shaft is arranged a disk 7 provided with a series of projecting lugs or studs 8, corresponding in

number and relative position to the several peripheral pockets of the delivery device. An operating handle 9 is loosely mounted on the shaft 6 and its supporting sleeve is provided at its inner end with an arm 10 on which is pivotally mounted a lever 11 having at its forward end a coin receptacle 12. The coin receptacle 12 is normally held beneath the lower end of a coin chute 13 by the action of a counterweight 14 and when a coin 15 is in said receptacle the lever 11 will be rocked so that a notch at the forward end thereof will be in alignment with the adjacent lug or stud 8 and adapted to turn the bottle delivering device when the handle 9 is rocked forwardly. It will be understood that normally when no coin is in the receptacle 12 forward movement of the handle 9 will not impart any movement to the bottle delivering device as at that time the forward end of the lever 11 will be in a plane entirely above that of the upper lug or stud 8. Therefore it is impossible to actuate the mechanism and withdraw a bottle from the machine except a proper coin has been previously deposited and received in the receptacle 12 which will act to rock the lever 11 into the position represented in Fig. 1.

As the bottle withdrawn from the chamber above the floor 2 is carried forward by the arms of the rotary delivery device, it will be discharged into the upper end of the chute 4, a hinged abutment or ejecting plate 17 being provided in said chute to check the downward movement of the bottle and permit it to gradually assume a substantially vertical position. The plate 17 is so located that it will be struck by the lower portion of the bottle as it leaves the delivery device and pushed or turned laterally against the side wall of the chute. As the delivery device is turned by operating the handle 9, after the depositing of a suitable coin in the receptacle at the forward end of the lever 11, as above explained, said receptacle will be carried into a position which will cause the coin carried thereby to fall from said receptacle and such coins may be collected in a chamber or compartment 18.

Within the casing of the machine is arranged a suitable coin reservoir shown as an open top tubular chamber in which coins corresponding in value to the empty bottles are stacked and means are provided whereby at each actuation of the delivery device one

of said coins will be withdrawn and can be subsequently delivered to the exterior of the machine as an empty bottle is returned to the receptacle provided therefor. As shown, 5 a reciprocating slide 21 is provided for ejecting the coins successively from the reservoir 20, said slide being guided in suitable guides on the machine frame and connected with a lever 22 by a link 23. The lever 22 is of such 10 form that it is given a complete oscillation in opposite directions at each actuation of the delivery device. As shown it is provided with two projecting members 22^a, 22^b, which are so related to the lugs 8 on the delivery 15 device that they will be successively engaged by two of such lugs at each intermittent rotary movement of the delivery device. As shown in Fig. 1, one of the lugs 8 is substantially in contact with the projecting 20 member 22^a of said lever, whereby during the first portion of the turning movement of the delivery device the lower end of said lever will be moved to the left acting to eject the lowest coin contained in the reservoir 25 20. During the latter portion of the turning movement of the delivery device the lug 8 which is engaged by the coin depressed lever 11 will contact with the cam surface on the member 22^b and rock said lever in 30 the opposite direction, thus restoring the slide 21 to a position where it will engage the next highest coin in the reservoir 20.

In addition to actuating the coin ejecting slide 21, the lever 22 is also adapted to turn 35 an oscillating "straw" delivery drum 24. As shown, this drum is suitably journaled at the lower end of a hopper 25 and a pinion 26 is attached to one end of its supporting shaft, said pinion being engaged by a 40 toothed segment 27 on the forward end of the lever 22. The "straw" discharged from the hopper 25 by the reciprocating motion of the lever 22 is delivered through a slot 28 into a suitable holder or receiver provided 45 therefor on the outer face of the frame 1 of the machine.

To positively limit the turning movement of the bottle delivering device and insure that the several lugs 8 thereof will be properly related and positioned relative to the 50 levers 11 and 22, a bent locking lever 29 is provided, one end of said lever being pivotally connected with the frame of the machine and the other being connected to a spring 30 55 which acts to hold it in such position that the members thereof will engage two of the lugs 8. It will be understood that as the delivery device is turned from the position indicated in Fig. 1, the lever 29 will be 60 rocked upwardly against the tension of the spring 30 until the lug 8 which is below the lower member thereof has passed to a position in front of the intermediate inclined member of said lever when the lever will

be quickly restored to the position shown in Fig. 1 by the action of said spring.

As shown, the coins ejected from the reservoir 20 are received in a holder 31 which is of substantially the same form as the reservoir 20 and as before explained one of said coins will be thus transferred at each actuation of the delivery device so that a considerable number thereof may be stacked in the holder 31. Means are provided whereby whenever a bottle is returned to the machine 75 the lowermost coin in the holder 31 will be delivered through a chute 32. The means provided for this purpose comprise a pivotally mounted bottle receiver 33 which as shown, is formed in a drum like casing 80 mounted on suitable trunnions or bearings on the machine frame and provided with a handle 34 by which it may be grasped and turned. The bottle receiver is slightly less in depth than the length of the bottles to be 85 placed therein, so that the bottom of a perfect bottle will project slightly beyond the periphery of the bottle receiving drum and into position to actuate a lever by which the coins are ejected from the holder 31. This 90 arrangement makes it necessary to insert a perfect bottle in the receiver in order to obtain the delivery of a coin from the machine and therefore bottles, the necks of which have been broken and which could not be 95 used again, may not be employed to operate the mechanism.

As the bottle receiver is turned the projecting end of the bottle therein strikes an arm 35^a of a lever 35 and rocks the same 100 downwardly. The lever 35 is provided with an arm 36 terminating in a projection 37 that engages a notch in a lever 38, the upper end of which is connected with a coin ejecting slide 39 coöperating with the 105 coin holder 31. Therefore as the lever 35 is rocked downward by engagement therewith of the projecting end of the bottle, the slide 39 will be moved forward to eject a coin from the holder 31 into the chute 32. 110 When the receiver has been turned sufficiently to bring the lower end of the bottle completely within the receptacle provided therefor or the chute leading thereto, the bottle will escape by gravity from the receiver slipping over the arm 35^a of the lever 35 and the parts referred to will then be returned to the position shown in Fig. 1 by the action of a counterweight 40 on the forward end of the lever 35.

To prevent the bottle receiver from being oscillated merely sufficiently to actuate the lever 35 possibly far enough to move the slide 39 and eject a coin and then returned to its normal position, without depositing 115 the bottle carried thereby in the receptacle provided for it in the machine, a plate 41 is provided. As shown, this plate is pivot-

ally supported at 42 on the frame of the machine and has its free end extending into contact with the curved wall of the bottle receiving casing. It can therefore yield upwardly and rearwardly sufficiently to permit the projecting end of the bottle in said receiver to pass but will positively prevent movement of said receiver in the opposite direction until after the bottle carried thereby has been deposited within the machine.

A plate 43 pivotally mounted at 44 and having lugs 45 bearing on the forward portion of the inclined bottle supporting floor 2 and a portion 46 extending into close proximity to the bottle receiver is provided for closing the lower forward end of the bottle receiving chamber of the machine. This chamber may be artificially cooled and said plate prevents the free introduction of warm air thereto. As the said plate is pivoted at its upper end it readily yields slightly rearward under the pressure exerted by the projecting end of a bottle in the receiver so that it does not offer any obstruction to said projecting end contacting with the arm 35^a of the lever 35.

It is thought that the operation and advantages of the invention will be readily understood and appreciated from the foregoing description and the drawings. It will be seen that a coin representing the value of an empty bottle will be withdrawn from the reservoir 20 and deposited in the holder 31 at each actuation of the delivery device which withdraws a bottle from the machine and that the coins will be in turn discharged from said holder by proper actuation of the bottle receiving and returning device without requiring further manipulation of the handle 9 of the bottle delivering device.

It will be seen that the mechanism described prevents the withdrawing of coins from the machine, by the return of empty bottles, unless there has been a corresponding, prior, actuation of the bottle delivery devices and consequent deposit in the machine of coins representing the value of an equal number of filled bottles.

In other words there can be no actuation of the bottle purchasing means except the selling mechanism has been previously and correspondingly actuated.

A number of sales may be made without immediate return of the bottles being required after each one, the coins corresponding to the number of bottles sold accumulating in the holder 31; but no coin will be deposited in said holder unless the bottle delivery device is operated and consequently the machine cannot be manipulated to exhaust the stock of coins representing empty bottles without the deposit of coins repre-

senting a corresponding number of sales and proper prior operation of the bottle delivery device.

While, as stated, the invention is particularly adapted for machines designed for selling bottled liquids, it will be readily appreciated that it may be employed for dispensing any articles where the containers have a redeemable value and the term bottle as employed in the present specification and claims is to be understood as covering all such containers. The "coins" referred to may of course be actual coins or if preferred merely disks of metal or other suitable material having a money exchange value, so that actual coins need not be employed in the machine unless desired.

Having described the invention what is claimed is:

1. In a machine for the purpose described, the combination of a support for a series of bottles, a delivery device adapted to withdraw bottles successively from said support, coin controlled means for intermittently actuating the delivery device, a coin reservoir, means for withdrawing a coin from said reservoir whenever the delivery device delivers a bottle, a holder for coins withdrawn from said reservoir, and means for delivering a coin from said holder adapted to be actuated by returning a bottle to the machine. 90

2. In a machine for the purpose described, the combination of a support for a series of bottles, a delivery device adapted to withdraw bottles successively from said support, coin controlled means for intermittently actuating the delivery device, a receptacle for empty bottles, two coin holders, means for transferring a coin from one of said holders to the other whenever a bottle is delivered by the delivery device, and means for discharging a coin from the last said coin holder when a bottle is deposited in said receptacle. 105

3. In a machine for the purpose described, the combination of a support for a series of bottles, a delivery device adapted to withdraw bottles successively from said support, coin controlled means for intermittently actuating the delivery device, a coin reservoir, means for withdrawing a coin from said reservoir whenever the delivery device delivers a bottle, a holder for coins withdrawn from the reservoir, a receptacle for empty bottles, a movable receiver adapted to deposit bottles in said receptacle, a lever having an arm extending into the path of a bottle in the receiver as the latter is moved to deposit the bottle in said receptacle, means actuated by said lever for withdrawing a coin from the holder, means for preventing movement of the bottle receiver in the opposite direction after said lever has been actuated until the bottle has been discharged 125

therefrom, and means for automatically returning said lever to normal position when the bottle is discharged from the receiver.

4. In a machine for the purpose described, the combination of a support for a series of bottles, a delivery device adapted to withdraw bottles successively from said support, coin controlled means for intermittently actuating the delivery device, a coin reservoir, a lever adapted to be reciprocated by movement of the bottle delivery device to successively eject coins from the reservoir, a holder for coins discharged from the reservoir, a receptacle for empty bottles, a movable receiver adapted to deposit a bottle in said receptacle, and means adapted to be actuated by a bottle in said receiver for withdrawing a coin from said holder as the receiver is actuated to deposit a bottle in said receptacle.

5. In a machine for the purpose described, the combination of a support for a series of bottles, a delivery device adapted to withdraw bottles successively from said support, coin controlled means for intermittently actuating the delivery device, a receptacle for empty bottles, a coin holder, a reciprocating slide adapted to be moved in one direction to withdraw a coin from said holder as a bottle is deposited in said receptacle, and means for automatically returning said slide to operative position when such bottle has been deposited.

6. In a machine for the purpose described, the combination of a support for a series of bottles, a delivery device adapted to withdraw bottles successively from said support, coin controlled means for intermittently actuating the delivery device, a receptacle for empty bottles, a coin holder, a rocking receiver adapted to deposit a bottle in said receptacle, a lever adapted to be rocked in one direction as said receiver is turned to deposit a bottle in said receptacle and to eject a coin from said holder, and means for automatically returning the lever to its former position as the bottle is discharged from the receiver.

7. In a machine for the purpose described, the combination of a support for a series of bottles, a delivery device adapted to withdraw bottles successively from said support, coin controlled means for intermittently actuating the delivery device, a receptacle for empty bottles, a coin holder, a movable receiver adapted to deposit a bottle in said receptacle, a lever adapted to be rocked in one direction by a bottle in said receiver to remove a coin from the holder as the receiver is moved to deposit the bottle in said receptacle, and means for automatically returning the lever to its former position when the bottle is discharged from the receiver.

8. In a machine for the purpose described, the combination of a support for a series of

bottles, a delivery device adapted to withdraw bottles successively from said support, coin controlled means for intermittently actuating the delivery device, a receptacle for empty bottles, a coin holder, a movable receiver adapted to deposit a bottle in said receptacle, a reciprocating slide adapted to successively withdraw coins from the holder, means for moving said slide in one direction adapted to be actuated by a bottle in the receiver, and means for automatically moving the slide in the opposite direction as the bottle is discharged from the receiver.

9. In a machine for the purpose described, the combination of a support for a series of bottles, a delivery device adapted to withdraw bottles successively from said support, coin controlled means for intermittently actuating the delivery device, a receptacle for empty bottles, a coin holder, a movable receiver adapted to deposit a bottle in said receptacle, a reciprocating slide adapted to successively withdraw coins from the holders, means for moving said slide in one direction adapted to be actuated by a bottle in the receiver, means for preventing movement of the receiver in the opposite direction after the bottle therein has actuated said slide until the bottle has been discharged, and means for automatically moving the slide in the opposite direction after the bottle has been discharged from the receiver.

10. In a machine for the purpose described, the combination of a support for a series of bottles, a delivery device adapted to withdraw bottles successively from said support, coin controlled means for intermittently actuating the delivery device, a coin reservoir, a lever adapted to be rocked in opposite directions at each actuation of the delivery device, means operated by said lever for withdrawing a coin from the reservoir, a holder to receive coins withdrawn from the reservoir, a receptacle for empty bottles, a movable receiver adapted to deposit a bottle in said receptacle, and means adapted to be operated by a bottle in said receiver, as the latter is moved to deposit the bottle in said receptacle, for withdrawing a coin from said holder.

11. In a machine for the purpose described, the combination of a support for a series of bottles, a rotary delivery device, adapted to withdraw bottles successively from said support, including a frame provided with a plurality of pins or lugs extending from one end, an operating handle provided with coin controlled means for engaging said pins or lugs successively, a coin reservoir, a lever adapted to be successively rocked in opposite directions by two of said pins or lugs at each operation of the delivery device, means actuated by said lever for withdrawing a coin from the reservoir, a holder for coins withdrawn from the reser- 130

voir, a receptacle for empty bottles, a bottle receiver movable to and from a position where it will deposit a bottle in the receptacle, and means adapted to be actuated by a 5 bottle in the receiver to discharge a coin from the holder as the receiver is moved to deposit the bottle in the receptacle.

12. In a machine for the purpose described, the combination of a support for a 10 series of bottles, a rotary delivery device adapted to withdraw bottles successively from the support, a plurality of lugs projecting from one end of the delivery device, coin controlled means for intermittently 15 turning the delivery device, a coin reservoir, a lever having members extending into the path of said lugs on the delivery device, whereby it will be oscillated in opposite directions at each operation of the delivery device, means actuated by said lever for successively withdrawing coins from the coin reservoir, a container for drinking "straws," means actuated by said lever for withdrawing one of said 20 "straws" from the container at each actuation of the delivery device, a holder adapted to receive the coins withdrawn from the reservoir, a receptacle for empty bottles, a bottle receiver movable to deposit a bottle 25 in said receptacle, and means adapted to be actuated by the bottle in said receiver for discharging a coin from the holder when the receiver is moved to deposit a bottle in the receptacle.

13. In a machine for the purpose described, the combination of a support for a 30 series of bottles, a delivery device adapted to withdraw bottles successively from said support, coin controlled means for intermittently actuating the delivery device, a receptacle for empty bottles, a pivotally mounted 35 bottle receiver adapted to deposit a bottle in said receptacle, a shield coöperating with the bottle receiver for preventing access of air past said receiver into the space above said bottle support, a coin holder, means 40 for depositing a coin in said holder at each actuation of the delivery device, and means for discharging a coin from said holder when the bottle receiver is actuated to deposit a bottle in said receptacle.

45 14. In a machine for the purpose described, the combination of a support for a series of bottles, a delivery device adapted to withdraw bottles successively from said support, coin controlled means for intermittently 50 actuating the delivery device, a receptacle for empty bottles, a pivotally mounted bottle receiver arranged below and in advance of the delivery device and adapted to deposit a bottle in said receptacle, a pivotally 55 mounted shield arranged between the delivery device and said bottle receiver, a coin holder, means for depositing a coin in said holder at each actuation of the delivery device, means adapted to discharge a coin 60 from the holder as the receiver is turned to deposit a bottle in the receptacle, and means arranged between said receiver and shield for preventing reverse movement of the receiver until the bottle therein is delivered.

15. In a machine for the purpose described, 65 the combination of a support for a series of bottles, a rotary delivery device adapted to withdraw bottles successively from the support, a plurality of lugs projecting from one end of the delivery device, coin controlled 70 means for intermittently turning the delivery device, a coin reservoir, a lever having members extending into the path of said lugs on the delivery device whereby it will be oscillated in opposite directions at each 75 operation of the delivery device, means actuated by said lever for successively withdrawing coins from the coin reservoir, a container for drinking "straws," means actuated by said lever for withdrawing one of said 80 "straws" from the container at each actuation of the delivery device, a holder adapted to receive the coins withdrawn from the reservoir, a receptacle for empty bottles, a bottle receiver movable to deposit a bottle 85 in said receptacle, and means adapted to be actuated by the bottle in said receiver for discharging a coin from the holder when the receiver is moved to deposit a bottle in the receptacle.

16. In a machine for the purpose described, the combination of a support for a series of bottles, a rotary delivery device adapted to withdraw bottles successively from the support, a plurality of lugs projecting from one end of the delivery device, coin controlled means for intermittently turning the delivery device, a coin reservoir, a lever having members extending into the path of said lugs on the delivery device 90 whereby it will be oscillated in opposite directions at each operation of the delivery device, a slide connected to said lever and co-operating with the coin reservoir to withdraw a coin therefrom at each actuation of 100 the delivery device, a holder for the coins withdrawn from the reservoir, a slide for successively discharging coins from said holder, a receptacle for empty bottles, a receiver adapted to deposit a bottle in said receptacle, and a lever connected with the coin 105 holder slide and adapted to be actuated by the bottle in said receiver as the latter is moved to deposit the bottle in the receptacle.

17. In a machine for the purpose described, the combination of a support for a series of bottles, a rotary delivery device adapted to withdraw bottles successively from the support, a plurality of lugs projecting from one end of the delivery device, coin controlled means for intermittently 120 turning the delivery device, a coin reservoir, a lever having members extending into the path of said lugs on the delivery device whereby it will be oscillated in opposite directions at each operation of the delivery device, means actuated by said lever for successively withdrawing coins from the coin 125

reservoir, a spring impelled device coöperating with the delivery device at the termination of each actuation thereof to properly position said lugs with relation to the lever, 5 a holder for coins withdrawn from the reservoir, a receptacle for empty bottles, a bottle receiver adapted to deposit a bottle in said receptacle, and means adapted to be actuated by the bottle in the receiver for discharging 10 a coin from the holder when the receiver is moved to deposit the bottle in said receptacle.

18. In a machine for the purpose described, the combination of a support for a 15 series of bottles, a rotary delivery device adapted to withdraw bottles successively from the support, a plurality of lugs projecting from one end of the delivery device, coin controlled means for intermittently turning 20 the delivery device, a coin reservoir, a lever

having members extending into the path of said lugs on the delivery device whereby it will be oscillated in opposite directions, at each operation of the delivery device, means actuated by said lever for successively with- 25 drawing coins from the coin reservoir, a spring impelled bent lever adapted to engage two of the lugs of the delivery device at the termination of each actuation thereof to maintain the proper relation between said 30 lugs and lever, a holder for coins withdrawn from the reservoir, a receptacle for empty bottles, a bottle receiver adapted to deposit a bottle in said receptacle, and means adapted to be actuated by the bottle in the receiver for discharging a coin from the 35 holder when the receiver is moved to deposit the bottle in said receptacle.

In testimony whereof I affix my signature.
HENRY JEFFERSON DAVIS.
